UNITED STATES PATENT OFFICE.

CAMPBELL C. CARPENTER, OF NIAGARA FALLS, NEW YORK, ASSIGNEE, BY MESNE ASSIGNMENTS, TO U. S. LIGHT & HEAT CORPORATION, OF NIAGARA FALLS, NEW YORK, A CORPORATION OF NEW YORK.

ELECTRICAL TERMINAL CONNECTION.

1,193,358.

Specification of Letters Patent. Patented Aug. 1, 1916.

Application filed November 19, 1914. Serial No. 872,972.

To all whom it may concern:

Be it known that I, CAMPBELL C. CARPENTER, a citizen of the United States, residing at Niagara Falls, in the county of Niagara and State of New York, have invented new and useful Improvements in Electrical Terminal Connections, of which the following is a full, clear, concise, and exact description, reference being had to the accompanying drawing, forming a part of this specification.

My invention relates to improvements in electrical terminal connections.

One manner of connecting battery cells together has been to join each pair of adjacent terminals with a bar of lead, or other suitable material. The bar is secured to the top of each terminal post by a bolt having one end embedded in the post, while the other end passes through an opening in the bar and is provided with a suitable clamping nut. The bolt is usually made of brass or other relatively hard metal, so that in service it sometimes becomes corroded to such an extent that its utility is destroyed, and a new one must be substituted. When this condition arises, an entire new terminal must be installed, as it is impossible to remove the corroded bolt from the post without destroying the post, due to the fact that the bolt is cast integrally therewith.

One of the objects of the present invention is to provide an electric terminal connection wherein the clamping device may be expediently attached to or removed from the terminal.

Another object of the invention is to provide an electric terminal connection in which the clamping device is protected from the corrosive action of battery acid and fumes.

Other objects of the invention will herein-after appear.

Referring to the embodiments of the invention as shown in the accompanying drawings, Figure 1 is a side view, partly in section, of two connected terminals. Fig. 2 is a sectional view of one of the terminals shown in Fig. 1, taken through the line 2—2, looking in the direction of the arrows, the clamping device being detached therefrom. Fig. 3 is a perspective view of the bolt and block

in which it is embedded. Fig. 4 is a sectional view of a modified form of the invention.

The terminals 1 and 2, in the construction illustrated, may be made of lead or other suitable material, and are each formed with a vertical post 3 attached to an elongated base 4, which may be connected with the plates of the battery. The terminals are connected together by a bar or link 5, which rests on the tops of the posts. The bar is formed with recesses 6 in its under side, near each end, which receive the tops of the terminal posts. The connecting bar is firmly secured to the top of each post by an improved clamping device, detachably secured to the post. This clamping device includes a frusto-conical-shaped block 7 formed of lead or other suitable material, which fits snugly into the upwardly tapering opening 8 that extends vertically through the post and base. A screw-threaded bolt 9 of brass or other relatively hard metal, is embedded in the upper end of the block. One end of this bolt extends vertically above the block and through the opening 10 in the connecting bar. The end of the bolt which is embedded in the block has an expanded hexagonal head 11, which prevents displacement of the bolt due to longitudinal or torsional stresses. A threaded clamping nut 12, arranged on the free end of the bolt, serves to clamp the connecting bar firmly in place. This nut is preferably formed of brass or other relatively hard metal, and is protected from corrosion by an inclosing casing 13 of lead. A washer 14, of antimonious lead, or other material, is interposed between the nut and the connecting bar. The casing of the nut is formed with a downwardly extending flange or skirt 15, to provide a housing for the washer. The inside diameter of the skirt is greater than the outside diameter of the washer, so that when the parts are assembled, an annular recess 16 is formed, which may be filled with vaseline, or other heavy oily substance, for the purpose of sealing up the joint made by the casing with the connecting bar. Both the tapered opening 8 in the terminal post and the recesses 6 in the connecting bar, may be provided

with a filler of vaseline, or other heavy oily substance, to exclude battery acid and fumes from the joints.

In order to prevent the tapered block from 5 turning or falling when the parts are being assembled, the base of the terminal is provided with a horizontal bore 17, which registers with the groove 18, formed across the end of the tapered block. A pin 19 of hard 10 rubber, or other suitable material, passes through the bore and the groove and serves to securely lock the block in position.

This improved construction possesses decided advantages over the old form of terminal connection in that the bolt may be readily removed from the post should it become corroded in service, and a new one substituted therefor; it being merely necessary to remove the block in which the bolt is 20 embedded from the post and insert another one in its place. Another important feature of this construction is that all of the hard metal parts, and especially the screw-threaded portions, are protected from the corrosive 25 action of the battery acid and fumes.

In Fig. 4 of the drawings, a modified form of clamping device is illustrated, in which the arrangement of the nut and bolt is reversed; the nut 20 being embedded in the 30 tapered block. In this construction the bolt 21 is formed with a head having an inclosing casing substantially the same as that employed with the nut illustrated in Fig. 1. If desired, the lead block may be dispensed 35 with and the bolt or nut modified in configuration to conform to the contour of the tapered opening in the post.

The embodiments of my invention described herein have been selected merely for 40 the purpose of illustration, and it is to be understood that the invention covers all equivalent means for accomplishing the desired results, so long as such means fall within the scope of the appended claims.

45 What I claim as new and desire to secure by Letters Patent of the United States, is—

1. Means for attaching a battery connector to a battery terminal lug including in combination, the battery terminal lug of relatively soft acid-proof material, said terminal having an opening therein, an insert of relatively hard conducting material in said opening, a battery connector, and means exerting a stress on said relatively hard 55 material for clamping said connector to said terminal, said insert being readily removable from said terminal without mutilating the parts, whereby said insert may be renewed or repaired without destroying the 60 terminal.

2. In combination, a battery terminal having a tapered aperture therethrough, a conducting member to be clamped to said terminal, a tapered screw-threaded member of 65 relatively hard material removably fitted in

said aperture, and a threaded nut carried by said tapered member, said tapered member and threaded nut coöperating to clamp said conducting member to said terminal.

3. In combination, a battery terminal having a tapered opening therethrough, a conducting member to be clamped to said terminal, a tapered threaded member removably fitted in said opening, and a threaded stud coöperating with said threaded tapered member, said tapered member and threaded stud coöperating to clamp said conducting member to said terminal. 70 75

4. In an acid-proof battery terminal connection, in combination, a terminal having an aperture formed therethrough, a conducting member, and a clamping device attached to said terminal for clamping said conducting member thereto, said device having a portion fitted in said aperture, said portion being so shaped that it can be removed only from one end of said aperture. 80 85

5. In combination, a battery terminal having an aperture therethrough, a conducting member, and a clamping device for clamping said conducting member to said terminal, said clamping device having a threaded portion fitted in said aperture, said portion being removable from one end only of said aperture, said clamping device also 90 95 having a threaded portion adapted to co-operate with the threaded portion fitted in said aperture to clamp said conducting member to said terminal.

6. In combination, a battery terminal having an aperture formed vertically therethrough and a substantially horizontal bore, a clamping device attached to said terminal, said device having a portion formed with a grooved end and fitted in said aperture, and a pin passing through said bore and groove whereby said clamping device is held against displacement. 100 105

7. A battery terminal lug of relatively soft acid-proof material and a relatively hard metallic insert in said terminal forming one of coöperating clamping members adapted to clamp a battery connector to the terminal, said insert being readily removable for renewal or repair without mutilation of the terminal lug. 110 115

8. In combination, a battery terminal lug of relatively soft material provided with a tapered opening, a hard metallic insert fitted in said opening but readily removable therefrom without mutilation of the lug, and an additional relatively hard member adapted to coöperate with said insert to clamp a separable battery connector to said lug. 120 125

9. In combination, a lead battery terminal having a tapered opening therethrough, a tapered lead plug removably fitted in said opening, an insert of relatively hard material in said plug, said insert being 130

provided with screw-threads, a separable battery connector adapted to be clamped to one end of the lug, and a screw-threaded member coöperating with the screw-threaded 5 insert to clamp said connector to said terminal.

In witness whereof, I have hereunto sub-

scribed my name in the presence of two witnesses.

CAMPBELL C. CARPENTER.
